DESIGN FOR AN AIRPLANE PROPELLER
BLADE

Arthur P. Leahy, Queens Village, N. Y.

Application June 13, 1947, Serial No. 139,637

Term of patent 14 years

(Cl. D71—1)

To all whom it may concern:

Be it known that I, Arthur P. Leahy, a citizen of the United States, residing at Queens Village, Long Island, in the county of Queens and State of New York, have invented a new, original, and ornamental Design for an Airplane Propeller Blade, of which the following is a specification, reference being had to the accompanying drawing, forming a part thereof.

In the drawing:

Fig. 1 is a top plan view of an airplane propeller blade, showing my new design;

Fig. 2 is a bottom plan view;

Fig. 3 is a front elevational view;

Fig. 4 is an end elevational view; and

Fig. 5 is a transverse sectional view taken on the line 5—5 of Fig. 2.

I claim:

The ornamental design for an airplane propeller blade, as shown.

ARTHUR P. LEAHY.
